FOREIGN PATENT DOCUMENTS

JP 2002-301421 A 10/2002

Primary Examiner — Austin Murphy

(74) *Attorney, Agent, or Firm* — Merchant & Gould P.C.

(57) **CLAIM**

The ornamental design for a plug for paint roller cover, as shown and described.

DESCRIPTION

FIG. 1 is a front perspective view of a plug for paint roller cover showing our new design.

FIG. 2 is a rear perspective view thereof.

FIG. 3 is a front plan view thereof.

FIG. 4 is a rear plan view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is another front perspective view thereof, the article being now shown lodged within a paint roller cover.

FIG. 10 is a front perspective view of a second embodiment of a plug for paint roller cover showing our new design.

FIG. 11 is a rear perspective view thereof; and,

FIG. 12 is another front perspective view thereof, the article being now shown lodged inside a paint roller cover.

The broken lines are for the purpose of illustrating environmental structure and form no part of the design.
